ROCK DRILL

Albert Feucht, Garfield Heights, Ohio, assignor to
The Cleveland Rock Drill Company, Cleveland,
Ohio, a corporation of Ohio

Application October 13, 1939, Serial No. 299,233

8 Claims. (Cl. 121—9)

This invention relates broadly to percussive machines, but more particularly to fluid actuated drilling apparatus of the stoper type.

One object of this invention is to improve the present mechanism for feeding and holding the drill to the work.

Another object of this invention is to provide the fluid actuated feeding mechanism of a stoper with an improved recoil checking mechanism preventing recoil movement of the drilling motor relative to the work during normal drilling operations.

Another object of this invention is to provide the fluid actuated feeding mechanism of a rock drill with a device calculated to maintain the drilling tool to the work irrespective of variations in the pressure of the motive fluid actuating the feeding mechanism.

Another object of this invention is the provision in a fluid actuated feeding mechanism for a rock drilling motor of a recoil checking mechanism which may be released by the simple manipulation of the main throttle normally controlling the admission of motive fluid to the drill motor.

Other objects and advantages more or less ancillary to the foregoing reside in the specific construction and aggroupment of the elements peculiar to this structure, as will become apparent from a more complete examination of this specification.

In the drawings:

Fig. 1 is a side elevational view of a stoper embodying the invention.

Fig. 2 is a longitudinal view of the improved feeding mechanism incorporated in the stoper shown in Fig. 1.

Fig. 3 is a cross sectional view taken in a plane indicated by line 3—3 in Fig. 2.

Figs. 4, 5, 6 and 7 are cross sectional views taken in a plane indicated by line 4—4 in Fig. 2, illustrating the throttle valve in different positions.

Figs. 8, 9, 10 and 11 are cross sectional views of the throttle valve taken in a plane indicated by line 8—8 in Fig. 2, illustrating the throttle valve in the same positions as shown in Figs. 4, 5, 6 and 7 respectively.

Figs. 12, 13, 14 and 15 are also cross sectional views of the throttle valve taken in a plane indicated by line 12—12 in Fig. 2 illustrating the throttle valve in the same positions as shown in Figs. 4, 5, 6 and 7 respectively.

Fig. 16 is an enlarged portion in section of the recoil checking mechanism shown in Fig. 2.

Fig. 17 is a view similar to Fig. 16 illustrating the recoil checking mechanism in inoperative position.

Fig. 18 is a cross sectional view taken in a plane indicated by line 18—18 in Fig. 2.

Fig. 19 is a longitudinal sectional view taken in a plane indicated by line 19—19 in Fig. 2.

Fig. 20 is a longitudinal sectional view of the central portion of the drilling motor taken in a plane indicated by line 20—20 in Fig. 1.

Fig. 21 is a longitudinal sectional view of the handle also shown in Fig. 1.

Fig. 22 is a view similar to Fig. 20 illustrating a modification of the invention.

Referring to the drawings, 25 represents the cylinder of the drilling motor within which is reciprocably mounted a piston (not shown) capable of delivering impacts on a drill steel 26 slidably mounted within a chuck 27, which is rotatably mounted within a front housing 28. Mounted coaxially with the cylinder 25, there is a head 29 against which rests the flange 30 of a feed cylinder or housing 31 depending from the cylinder 25 in coaxial relation therewith. The front housing 28, head 29 and flange 30 are rigidly secured to the cylinder 25 by two side bolts 32.

Slidably mounted within the feed cylinder 31, there is a piston cylinder 33 closed at its lower end by a plug 34 carrying a removable ground 35 engaging pointed end 35. On the inner end, the piston cylinder 33 carries a piston 36 equipped with packing rings 37 in fluid tight slidable engagement with the inner wall of the feed housing 31. This piston rests on an annular shoulder 38 formed on the cylinder 31 and is held in position by a retaining nut 39. The cylinder 33 is formed with a buttless internal screw thread 40 having a straight face 41 and an outwardly inclined face 42, the thread being of an angle of about two to three degrees, thereby actually producing the equivalent of annular ratchet teeth formed on the inner wall of the piston cylinder 33.

Depending from the head 29 into the piston cylinder 33, there is an inner tube 43 slidably mounted within the piston cylinder 33. This inner tube is closed at its lower end by a plug 44 formed with an arcuated seat 45 extending laterally therethrough and within which is swingably mounted the trunnion 46 of a pawl 47 depending therefrom and having a semicircular wedge-shaped operating edge 48 engageable with the flat face 41 of the teeth or threads 40, as clearly shown in Fig. 16. At a place diametrically op-

posed to the operating edge of the pawl 47, the plug 44 is provided with a depending lug 49 against which rests a spring pressed plunger 50 radially carried by the pawl 47 for constantly urging the pawl in engagement with the thread 40. Intermediate its ends, the trunnion 46 of the pawl 47 is provided with a slot 51 formed with an inclined bottom wall 52 leading toward the operating edge 48 of the pawl.

Within the flange 30, there is provided a chamber 53 closed at its upper end by the head 54 of a gland 55 screwed within the adjacent portion of the head 29, which gland holds in position a water tube 56 through which cleansing fluid is admitted to the free end of the drill steel 26. Slidably mounted within the chamber 53, there is the cylindrical head 57 of a rod 58, which rod extends into the inner tube 43 for end engagement with the bottom wall 52 of the slot 51 provided in the pawl 47. Interposed between the head 57 of the rod 58 and the gland 54, there is a compression spring 59 constantly urging the rod 58 downwardly, while the chamber 53 above the head 57 is constantly vented to the atmosphere through a port 75.

30 Formed on the head 29, there is a laterally projecting boss 60 within which is rotatably mounted a throttle valve 61 having a shank 62 extending through one end of the boss to receive, an operating handle 63. Swivelly mounted within the other end of the boss 62, there is a motive fluid connection 64 through which motive fluid may be admitted into a central bore 65 provided in the throttle valve 61. Toward its shanked end, 35 the peripheral wall of the throttle valve 61 is provided with a semicircular groove 66 capable of communication with a vent 67 leading from the valve to the atmosphere and with a port 68 leading in the bottom of the chamber 53 within, 40 which is slidably mounted the head 57 of the rod 55. Within the same vertical plane of the annular groove 66, the throttle valve is also provided with a radial port 69.

45 Longitudinally spaced from the groove 66, the valve 61 is also provided with an enlarged radial port 70 of V-shaped cross section capable of communication with a passage 70' leading into the cylinder 25, and in the same vertical plane with a semicircular groove 71. From this groove leads 50 a longitudinally extending groove 72 ending within a vertical plane adjacent the inner end of the throttle valve and capable of communication with a port 72' leading in the upper end of the feed housing 31. Within the last named vertical 55 plane, the throttle valve is also provided with a semicircular groove 73 in constant communication with the valve bore 61 through a port 74.

In Fig. 20 there is shown the usual feed release port 76 leading from the upper end of the feed cylinder 31 to the shank 77 of a handle 78 extending laterally from the cylinder 25 in the usual manner. This port 56 is normally controlled by a spring seated valve 79 movable into open position by a slideable rod 80 operable through a hand operated cam 81. When the valve 79 opens, as shown in Fig. 21, motive fluid from the feed cylinder may exhaust to the atmosphere through an exhaust port 82.

In Fig. 22, there is shown a modification of the invention including a port 83 connecting the bottom of the chamber 53 with the upper end of the feed cylinder 31, the purpose of which will be explained later.

In the operation of the device, with the throttle valve as shown in Figs. 4, 8 and 12, the motive

fluid admitted into the bore 65 of the throttle valve through the connection 64 is prevented from flowing into the machine and the feeding mechanism, thereby preventing operation of the drilling apparatus. As the throttle is rotated from the position shown in Fig. 12 to that in Fig. 13, motive fluid from the throttle valve bore 65 admitted into the valve groove 73 through the port 74, will flow into the upper end of the feed cylinder 31 through the port 72', thereby acting on the piston 36 causing feeding motion of the drilling motor 45 toward the work. In this instance, it will be noticed that the inlet port 70 is still spaced from the port 70', thereby enabling feeding of the drill without admitting motive fluid into the drilling motor 25. In this last position of the valve, its inlet port 69 in Fig. 5, is still spaced from the supply port 68 to the bottom of the chamber 53, thereby causing the rod 58 to assume a downward extreme position relative to the inner tube 43 and consequently exerting pressure on the inclined bottom wall 52 of the pawl's slot 46 for maintaining the pawl 47 out of engagement with the threads 40.

As the throttle valve is rotated from the position shown in Fig. 13 to that in Fig. 14, motive fluid is still supplied to the feed cylinder 31 through the valve groove 73 and supply port 72. In this new position of the throttle valve, the narrow portion of the V-shaped inlet passage 70 is in communication with the port 70' for admitting a limited amount of motive fluid to the cylinder 25 for effecting reciprocation of the hammer in a manner calculated to deliver light impacts to the drill steel 26, a condition which has been found desirable when starting the drill hole. In this position of the throttle valve, it will be seen that the valve port 69 is still in spaced relation with the supply port 68, thereby enabling the rod 58 to remain in operative engagement with the pawl 47 for holding it in inoperative position.

After the throttle valve has been rotated into full operative position as shown in Figs. 7, 11 and 15, the supply of the motive fluid to the feed cylinder still takes place through the valve groove 43 and port 12'. In this instance, the valve supply passage 70 is in full communication with the passage 70', while the valve port 69 is now in communication with the supply port 68, thereby admitting motive fluid to the bottom of the chamber 53 to act under the head 57 of the rod 58 for moving the rod and head into the position shown, in Fig. 2 against the effect of the compression spring 59, consequently enabling the spring pressed plunger 50 to move the pawl 47 into operative engagement with the ratchet teeth 40. As the drilling operation proceeds, the drilling motor 25 together with the inner tube 43 and consequently with the pawl 47 will move upwardly relative to the piston tube 33. In this instance, the pawl 38 pressed by the spring pressed plunger 50 will simply ride the ratchet teeth 40 and successively engage the flat faces 41 thereof to prevent recoil movement of the drilling motor relative to the feed piston 33, thereby maintaining the drill steel 26 in engagement with the work and preventing up and down motion of the drilling motor.

When it is desired to release or disengage the recoil checking mechanism, the operator may move the throttle valve 61 into any of the positions shown in Figs. 4 to 6, in which instance the supply port 68 leading from the bottom of the chamber 53 is put in communication with the atmosphere through the vent or exhaust port 67. 70

thereby relieving the pressure under the head 57 of the rod 58 and enabling the compression spring 59 to drive the rod downwardly for causing the disengagement of the pawl 47 with the 5 ratchet teeth 48 as clearly shown in Fig. 17.

In the modification shown in Fig. 22, the ports and passages shown in Figs. 4 to 7 inclusive may be omitted. In this instance, the bottom of the chamber 53 is in direct communication with the 10 upper end of the feed cylinder 31 through the port 83, thereby causing the rod 58 to assume the position shown in Fig. 16 as soon as motive fluid is admitted into the air feed cylinder, that is, in any position of the throttle valve shown 15 in Figs. 13 to 15, and consequently enabling the operative engagement of the pawl 47 with the ratchet teeth 48. In this instance, the disengagement of the pawl will take place when the motive fluid pressure is released from the feed cylinder 20 31 by the operator actuating the cam 81 for opening the valve 79, thereby enabling free exhaust of the motive fluid via the port 16, the now opened valve 79 and the exhaust port 82, and resulting in a drop of pressure in the chamber 53 25 permitting the spring 59 to drive the rod 58 downwardly to cause the disengagement of the pawl 47.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

I claim:

1. In a drilling apparatus, the combination 40 with a drilling motor, of a feeding mechanism for said motor including a feed housing fixed to the motor, a fluid actuated piston cylinder telescopically mounted in said housing, of an inner tube in said cylinder fixed to said motor, longitudinally spaced teeth on the inner wall of said cylinder, a pawl pivotally carried by the inner end of said tube for operative engagement with said teeth to prevent recoil movement of the motor relative to said cylinder, and a rod slidably 45 in said tube engageable with said pawl for effecting its disengagement from said teeth to permit the collapse of said feeding mechanism.

2. In a drilling apparatus, the combination 55 with a drilling motor, of a feeding mechanism for said motor including a feed housing fixed to the motor, a fluid actuated piston cylinder telescopically mounted in said housing, of an inner tube in said cylinder fixed to said motor, longitudinally spaced teeth on the inner wall of said cylinder, a pawl pivotally carried by the inner end of said tube for operative engagement with said teeth to prevent recoil movement of the motor relative to said cylinder, and means in said tube operatively engageable with said pawl for effecting its disengagement from said teeth to permit the collapse of said feeding mechanism.

3. In a drilling apparatus, the combination 60 with a drilling motor, of a feeding mechanism for said motor including a feed housing fixed to the motor, a fluid actuated piston cylinder

telescopically mounted in said housing, a throttle valve for controlling admission of the motive fluid to said piston cylinder, of an inner tube in said cylinder fixed to said motor, longitudinally spaced teeth on the inner wall of said cylinder, a 5 pawl pivotally carried by the inner end of said tube for operative engagement with said teeth to prevent recoil movement of the motor relative to said cylinder, a rod slidably in said tube engageable with said pawl for effecting its disengagement from said teeth to permit the collapse of said feeding mechanism, and means including said throttle valve for controlling the 10 slidable movement of said rod.

4. In a drilling apparatus, the combination 15 with a drilling motor, of a feeding mechanism for said motor including a feed housing fixed to the motor, a fluid actuated piston-cylinder telescopically mounted in said housing, of a recoil 20 checking mechanism comprising a tube in said cylinder fixed to said motor, longitudinally spaced teeth on the inner wall of said cylinder, a pawl carried by said tube operatively engaging said teeth, and means effecting disengagement of said pawl from said teeth.

5. In a drilling apparatus, the combination 25 with a drilling motor, of a fluid actuated feeding and supporting mechanism for said motor including a feed housing fixed to the motor having a piston-cylinder telescopically mounted 30 therein, a throttle valve for controlling admission of motive fluid to said mechanism, of a recoil checking device between said motor and cylinder, a 35 slidable rod in said housing operatively associated with said device for rendering it inoperative, and means including said throttle valve for controlling slidable movement of said rod.

6. In a support for a drilling motor, a pair of 40 telescopically mounted elements, means including a throttle valve for admitting motive fluid in the outer element for effecting the extension stroke of said elements, a releasable lock between said elements normally preventing the compression stroke thereof, and means controlled 45 by said throttle valve for effecting the release of said lock.

7. In a support for a drilling motor, a pair of 50 telescopically mounted elements, means including a throttle valve for admitting motive fluid to said elements for effecting the extension stroke thereof, a releasable lock between said elements normally preventing the compression stroke thereof, a 55 slidable rod operatively engageable with said lock for effecting its release, and means including said throttle valve for controlling the slidable movement of said rod.

8. In a support for a drilling motor, a pair of 60 telescoping cylinders, means for admitting motive fluid to said cylinders for effecting the extension stroke thereof, a locking device for said cylinders normally preventing the compression stroke thereof including longitudinally spaced teeth on one of said cylinders, a pawl successively engaging said teeth during the extension stroke of said cylinders for normally preventing said compression stroke, and means for shifting said pawl out of engagement with said teeth to permit said compression stroke.

ALBERT FEUCHT. 70
